UNITED STATES PATENT OFFICE.

HENRY G. ROTH, OF MINNEAPOLIS, MINNESOTA.

DESIGN FOR A DISPLAY-FIXTURE FOR STORES.

SPECIFICATION forming part of Design No. 31,526, dated September 19, 1899.

Application filed July 17, 1899. Serial No. 724,143. Term of patent 7 years.

To all whom it may concern:

Be it known that I, HENRY G. ROTH, a citizen of the United States, residing at Minneapolis, in the county of Hennepin, Minnesota, 5 have invented and produced a new and original Design for a Display-Fixture for Stores, of which the following is a specification, reference being had to the accompanying drawing, forming a part thereof.

- In said drawing the single view is a perspective, partly in section, illustrating a display-fixture for stores embodying my invention.

As therein shown, the leading or material 5 features of my design are the columns *a*, the capitals or head-pieces *b*, the arch or connecting plates *c*, and the cove-plates *d*, with said parts disposed relative to each other, as shown.

- The columns *a* are shown as rising from the outermost member 1 of a series of shelves 1 2 3, forming the upper portion of the display shelving, some other parts of which are shown at 4 and 5. The columns *a* are of circular form and are shown as if made up of 25 a series of sections.

The capitals or head-pieces *b* are of spear-head shape. The arch or connecting plates *c* and the edges of the capitals are cut to the

form of a continuous curve, so as to give the 30 appearance of a true arch.

The cove-plates *d* curve outward and co-operate with retaining-plates *e* and *f*, projecting, one horizontally and the other on a downward incline, from the room-wall *h* to afford 35 a heavy cornice.

The head-pieces *b*, the arch-plates *c*, and the cove-plates *d* are in practice usually covered with paint or paper in suitable contrasting colors.

With the parts *a*, *b*, *c*, and *d* disposed as above described a colonnade canopy is afforded to the display shelving, which adds greatly to the artistic effect.

This design is especially intended for use 45 in groceries and other stores for displaying canned and bottled goods.

Having thus described my invention, what I claim as new, and desire to secure by Letters Patent of the United States, is as follows:

The design for a display-fixture for stores, substantially as herein shown and described.

In testimony whereof I affix my signature in presence of two witnesses.

HENRY G. ROTH.
